UNITED STATES PATENT OFFICE.

JOHN R. GAMMETER AND HARRY DEWHIRST, OF AKRON, OHIO, ASSIGNEES TO THE
B. F. GOODRICH COMPANY, OF NEW YORK, N. Y., A CORPORATION OF NEW YORK.

SHOE HEEL.

Application filed May 11, 1922. Serial No. 560,021.

To all whom it may concern:

Be it known that we, JOHN R. GAMMETER and HARRY DEWHIRST, citizens of the United States, residing at Akron, in the county of Summit and State of Ohio, have invented a certain new and useful Shoe Heel, of which the following is a specification.

This invention relates to cushion heels of composite structure, including a soft-rubber tread or cushion portion, and a relatively-stiff upper attaching portion which is extended downwardly to or toward the lower tread face at certain parts such as the heel-breast, to provide additional stiffness and support in that part. It is common to mold the nail-holes in a rubber heel inwardly to the stiffening member or members for retaining the nail-heads, but heretofore in composite heels of the type mentioned having a hard-rubber attaching and breast portion, it has been a difficult matter to secure the most desirable combination of stiff and resilient properties in the different parts of the heel without forming the front row of nail-holes in the hard-rubber part, which left relatively large openings for the withdrawal of the molding-pins, which holes had to be filled with plugs after the heel was nailed to the shoe, in order to exclude foreign substances. Our object in the present invention is to avoid this difficulty and furnish a composite heel in which all of the nail-holes are or may be formed in the soft rubber, which allows the holes to be made slightly smaller than the nail-heads, and thus nearly to close thereover when the nails are driven in place.

Of the accompanying drawings, Fig. 1 is a reverse plan view showing a preferred embodiment of our invention in the form of a heel-lift, with adjacent parts of the shoe in broken lines.

Fig. 2 is a section on the line 2—2 of Fig. 1.

Fig. 3 is a reverse plan view showing a modified construction.

Fig. 4 is a vertical, longitudinal section showing a second modification.

Referring at first to Figs. 1 and 2, 10 is a plate-like attaching member made of relatively hard or stiff rubber compound, preferably intermixed with cotton fiber, the said

member being extended downwardly at 11 to the lower tread surface at its front edge portion, so as to constitute the entire breast 55 part of the heel-lift as well as the forward part of the tread face. 12 is a soft-rubber member integrally vulcanized to the hard-rubber part 10 and constituting most of the tread portion of the heel-lift, including its 60 lower rear edge where the cushioning action is most desirable in walking.

13, 13 are the attaching nails and 14, 14 are narrow nail-holes molded in the soft-rubber as far as the attaching member 10. 65 The forward part 11 of the hard-rubber element is extended rearwardly at 15, 16 on either side of and between the nail holes in a series of U-shaped indentations or scallops, thereby securing ample strength and 70 width of tread surface in the stiffened breast portion 11 without bringing the front row of nail-holes in said stiffened portion.

In some cases we may omit the scallops and make the stiffened breast portion 11^a of 75 a relatively smaller maximum width in a fore-and-aft direction and the soft-rubber part 12^a of a relatively greater minimum width, as indicated in Fig. 3, the line of junction here being parallel to the breast 80 edge.

In other cases we may terminate the stiffened breast portion 11^b above the tread surface and extend the soft-rubber part 12^b forwardly so as to underlie said stiffened 85 breast portion at 17 and form the entire tread surface, as shown in Fig. 4.

We claim:

A rubber heel comprising a hard-rubber attaching member forming the top and 90 breast portions of the heel and extended downwardly to the lower tread surface at the breast edge, and a soft-rubber tread portion vulcanized to said attaching portion and formed with nail holes, the said breast 95 portion being formed with indentations occupied by forward projections on the soft-rubber portion in which are located the front row of nail holes.

In witness whereof we have hereunto set 100 our hands this 8 day of May, 1922.

JOHN R. GAMMETER.
HARRY DEWHIRST
